US0D1052609S

(12) **United States Design Patent** (10) Patent No.: **US D1,052,609 S**
(45) Date of Patent: ** Nov. 26, 2024

(54) **DISPLAY SCREEN WITH GRAPHICAL USER INTERFACE**

(71) Applicant: **NEC Corporation**, Tokyo (JP)

(72) Inventors: **Hiroaki Takeuchi**, Tokyo (JP); **Ryo Kawai**, Tokyo (JP); **Noboru Yoshida**, Tokyo (JP); **Jianquan Liu**, Tokyo (JP); **Yuta Namiki**, Tokyo (JP); **Naoki Shindou**, Tokyo (JP); **Youhei Sasaki**, Tokyo (JP)

(73) Assignee: **NEC CORPORATION**, Tokyo (JP)

(**) Term: **15 Years**

(21) Appl. No.: **29/867,699**

(22) Filed: **Nov. 4, 2022**

(30) **Foreign Application Priority Data**

May 31, 2022 (JP) ..... 2022-011662 D

(51) LOC (14) Cl. **14-04**

(52) U.S. Cl.

USPC **D14/486**

(57) **CLAIM**

The ornamental design for a display screen with graphical user interface as shown and described.

DESCRIPTION

FIG. 1 is a front elevational view of a display screen with graphical user interface showing our new design. The broken lines illustrate portions of the display screen with graphical user interface and form no part of the claimed design. The long dot-dash broken line illustrates a boundary of the claimed design and forms no part of the claimed design.

1 Claim, 1 Drawing Sheet
